UNITED STATES PATENT OFFICE.

HOWARD H. WESSEL, OF NEW BRITAIN, CONNECTICUT, ASSIGNOR TO THE HART & COOLEY MANUFACTURING COMPANY, OF NEW BRITAIN, CONNECTICUT, A CORPORATION OF CONNECTICUT.

DESIGN FOR A BOOK END.

Application filed February 4, 1927. Serial No. 20,615. Term of patent 14 years.

To all whom it may concern:

Be it known that I, HOWARD H. WESSEL, a citizen of the United States, residing at New Britain, county of Hartford, and State of Connecticut, have invented a new, original, and ornamental Design for Book Ends, of which the following is a specification, reference being had to the accompanying drawing, forming part thereof.

Fig. 1 is a perspective view of the book-end.

Fig. 2 is an end view of the same.

I claim:

The ornamental design for a book-end as shown.

HOWARD H. WESSEL.
